PAIR OF NOVELTY SUNGLASSES

Marvin I. Glass and Henry Stan, Chicago, Ill., assignors
to Marvin Glass & Associates, Chicago, Ill., a partnership

Filed May 20, 1965, Ser. No. 85,364

Term of patent 14 years

(Cl. D57—1)

FIGURE 1 is a perspective view of a pair of novelty sunglasses showing our new design;

FIGURE 2 is a top plan view thereof;

FIGURE 3 is a side view thereof;

FIGURE 4 is a bottom plan view thereof; and

FIGURE 5 is a rear view of the sunglasses.

The dominant features of our design reside in the portions shown in full lines. The temple portions have been omitted in FIGURES 2-5 for convenience of illustration.

We claim:

The ornamental design for a pair of novelty sunglasses, substantially as shown and described.
